ELECTRIC SWITCH

Joseph A. Clinton, Rocky Hill, Conn., assignor to
 Colt's Patent Fire Arms Manufacturing Company, Hartford, Conn., a corporation of Connecticut

Application April 15, 1937, Serial No. 137,091

4 Claims. (Cl. 200—114)

The invention relates to electric switches, and more particularly to switches which include circuit overload protecting means such as fuses.

The principal object of the invention is to provide a switch construction including a casing therefor wherein there is provided a main cover which when closed prevents access to the switch circuit connectors but does permit access to certain other parts of the switch, and on which is mounted an auxiliary cover openable therewith and also independently thereof and which carries an electrical conductor adapted to electrically connect the switch contacts under certain conditions.

From the following specification other objects and advantages of the invention will be apparent to those skilled in the art.

In the accompanying drawings I have shown the embodiment of the invention which I now deem preferable, but it will be understood that the drawings are intended for illustrative purposes only and are not to be construed as defining or limiting the scope of the invention, the claims forming a part of this specification being relied upon for that purpose.

In the drawings:

Fig. 1 is a front elevation of a switch embodying the principles of the invention.

Fig. 2 is a view similar to Fig. 1 but showing the auxiliary cover in open position.

Fig. 3 is a view similar to Fig. 1 but showing both covers in open position.

Fig. 4 is a sectional view taken on the line 4—4 of Fig. 1 with certain parts broken away to more clearly show the construction.

Fig. 5 is a sectional view taken on the line 5—5 of Fig. 1.

In accordance with the invention a casing is provided which may be of any desired type and in the drawings I have illustrated the casing as comprising a channel member 1 having removable side walls 2. The channel and side walls may be provided with such "knockouts" as may be considered desirable. I now prefer the form of casing illustrated because it may be incorporated in a troughing system such as shown in the patent to Sachs No. 1,758,981 issued May 20, 1930.

In the casing I mount means for supporting the several elements of the switch. An insulating block 3 constitutes such a supporting means and it is stationarily mounted by screws 4 on a bracket 5 which is in turn secured in the casing.

In the illustrated embodiment I have shown two identical switches and associated circuits but it

should be understood that any number of switches could be provided and that they could be of identical or different constructions as desired. As my two switches are identical I will only describe one.

On the block 3 are mounted line and load circuit connectors 6 and 7, respectively, which are preferably so mounted as to be readily accessible under certain conditions for connection purposes. On the block 3 I also mount at least one switch contact and provide means for electrically connecting this contact with one of the circuit connectors. I have shown two switch contacts 8 and 9 mounted on the block and each one is electrically connected with a circuit connector. At least one of the contacts is so positioned that a person would not ordinarily touch it and thereby receive a shock. In the preferred construction illustrated both of the contacts 8 and 9 are so positioned as to effectively prevent accidental contact therewith. These contacts are preferably embedded in the block 3 in recesses 10 which open into the surface 11 of the block and form the apertures 12 therein, the contact 8 being secured to the block by a screw 13. It should be noted that these contacts in the preferred construction lie behind the plane of the surface 11, and are not only positioned in recesses in the block but are also aligned with the apertures 12 in the surface 11. I do not, however, wish to limit myself to either of these details, the same being merely preferred rather than critical.

A fused type of switch is shown, this being the form of switch to which the principles of my invention are particularly applicable. In accordance with the invention the fuse is preferably interposed in the circuit connecting one of the switch contacts with the load circuit connector 7 and is so positioned as to be accessible for replacement. In the drawings I have shown a fuse receiving means 14 which is mounted on the block 3 to hold a fuse in such a position that it is accessible from the front of the casing for replacement. A center fuse contact 15, which is screw threaded, is secured to an angular extension 16 on the contact 9 to thereby electrically connect the two and to secure the contact 9 to the base. The threaded shell contact 14 is connected to the load circuit connector 7.

In accordance with the invention an openable main cover having an aperture therein is provided for closing the front of the casing. The cover is so related to the casing and block 3 that, when closed, access to the circuit connectors 6 and 7 is prevented but access to at least a portion of the block is permitted. The main cover 17 is

hinged to the casing as indicated at 18 and includes an apertured portion 19. It is apparent from the drawings, note Figs. 2 and 4 in particular, that I have shown a construction for effectively preventing access to the circuit connectors while permitting access to at least a portion of the block 3, and more particularly to at least that portion of the block on which a fuse is adapted to be mounted so that the fuse may be replaced without opening the main cover.

The main cover may be secured in closed position in various ways but I have shown a construction which I now consider preferable. The block 3 has a hole 20 formed therein in which is secured a nut 21. The main cover has a hole therethrough at 22 and a bolt 23 projecting through the hole for engaging the threads of the nut 21 constitutes a releasable means for securing the main cover in closed position. The bolt 20 may, of course, be omitted if desired. The casing is also provided with the apertured spring latch 24 which is adapted to project through a hole 25 in the cover when closed.

I provide an auxiliary cover for closing the aperture in the main cover, the auxiliary cover being mounted on the main cover so as to be movable to expose the aperture in the latter and also so as to be movable with the main cover. The movement of the auxiliary cover with respect to the main cover may be of any desired type, but this will be dependent upon other details of construction. In the illustrated and now preferred form of the invention, an auxiliary cover 26 is hinged to the main cover at 27 and includes an offset or domed portion 28. The auxiliary cover 26 is larger than the aperture in the main cover and, therefore, when closed serves to not only cover the aperture but to also cover the main cover securing bolt 23. The main cover is preferably offset at 29 to permit the edges of the auxiliary cover to lie flush with the outer surface of the main cover and may be apertured as at 30 to receive a spring latch 31 on the auxiliary cover. It is apparent that the two covers 17 and 26 will move as a unit when the main cover is opened. A handle, such as shown at 32 may be provided on the auxiliary cover.

The auxiliary cover has mounted thereon, and insulated therefrom, an electrical conductor 50 which projects rearward therefrom. This conductor is so positioned and dimensioned that it electrically connects the switch contacts in the casing when both the main and auxiliary covers are closed and is electrically disconnected from at least one of them when either the main or auxiliary cover is open. In the embodiment shown an electrical conductor 33 is secured to the auxiliary cover 26 by means of an insulating block 34 which is secured to the offset portion 55 28 of the cover. In the illustrated form, the switch contacts 8 and 9 are mounted in separate recesses in the block 3 and the conductor 33 is accordingly provided with two legs 35 which are adapted to project through the apertures 12 60 in the surface 11 of the block to electrically connect the switch contacts.

The ends of the switch contacts 8 and 9 and the legs 35 are preferably beveled to provide co-operating cam surfaces 36 and 37 for assuring 70 the proper engagement of these members when the conductor legs 35 are being moved into engagement with the switch contacts.

In using my device, either or both of the covers may be sealed shut by padlocks, for example, secured to the latch 24 and rings 38, and the main

cover may, if desired, be additionally fastened by the bolt 23.

The particular fused switch shown is adapted for use with a three wire system and for this reason I have shown a solid neutral 39 mounted 5 on the block 3.

The operation of the device illustrated will now be described, assuming first that the switch is suitably mounted and properly connected in an electrical circuit. If the auxiliary cover is sealed 10 in closed position, the seal is first removed. By means of the handle 32 the auxiliary cover 26 may now be moved to open position and while being so moved the conductor 33 is moved out of engagement with the switch contacts 8 and 9 15 to thereby electrically disconnect them. As the contacts 8 and 9 are positioned behind the surface 11 there is little or no danger of accidentally touching these contacts. Also with just the auxiliary cover open no access may be had to the 20 circuit connectors 6 and 7. The connector 1 is preferably connected to the load side of the circuit and consequently with the auxiliary cover open so as to expose the fuse for replacement the fuse contacts 14 and 15 are electrically dead. 25 The fuse may now be replaced without danger of shock to the person so replacing it. The auxiliary cover may now be closed, movement of the conductor 33 being simultaneously effected to electrically connect the switch contacts 8 and 30 9. If access to the circuit connectors 6 and 7 is desired for any reason, the main cover may be opened after first releasing the latch 24, or if a bolt 23 is used it must be removed; in either case, it is apparent that the switch contacts 8 and 9 35 will be electrically disconnected when the main cover is open to expose the circuit connectors.

It is of course obvious that various changes in details of construction within the scope of the invention will be apparent to those skilled in the 40 art.

What I claim is:

1. The combination in a fused electric switch, of a casing, an insulating block stationarily mounted within the casing and having a front 45 surface, an openable main cover for the casing having an opening therein, the edges of the opening substantially fitting the block and the cover thus cooperating with the block to entirely close the casing with only the front face of the block 50 exposed, line and load circuit connectors mounted on the block behind the cover, two switch contacts mounted on the block behind the front surface thereof so as to be substantially protected thereby from being accidentally touched, one of 55 said contacts being electrically connected with in the casing with one circuit connector, fuse receiving contacts mounted on the block adjacent the front surface thereof so as to be accessible through the cover opening for fuse replacement, 60 the said fuse contacts being electrically connected within the casing with said other switch contact and with the other circuit connector respectively, an openable auxiliary cover mounted to be movable with the main cover and normally 65 serving to close the opening therein and to cover said exposed front surface of the block, and an electrical conducting member carried by the auxiliary cover and insulated therefrom and being so formed and positioned as to engage and electrically connect the switch contacts when the auxiliary cover is closed and to electrically disconnect said contacts when either the main or auxiliary cover is open.

2. The combination in a fused electric switch, 75

of a casing, an insulating block stationarily mounted within the casing and having a front surface with at least one relatively small aperture therein, an openable main cover for the casing 5 having an opening therein, the edges of the opening substantially fitting the block and the cover thus cooperating with the block to entirely close the casing with only the front face of the block exposed, line and load circuit connectors mounted 10 on the block behind the cover, a switch contact mounted on the block behind the front surface thereof in alignment with said aperture therein so as to be substantially protected from being accidentally touched, said contact being electrically 15 connected within the casing with the line circuit connector, a second switch contact mounted on said block, fuse receiving contacts mounted on the block adjacent the front surface thereof so as to be accessible through the cover opening for 20 fuse replacement, the said fuse contacts being electrically connected within the casing with said second switch contact and with the load circuit connector respectively, an openable auxiliary cover mounted to be movable with the main cover 25 and normally serving to close the opening therein and to cover said exposed front surface of the block, and an electrical conducting member carried by the auxiliary cover and insulated therefrom and being so formed and positioned as to engage and electrically connect the switch contacts when the auxiliary cover is closed and to electrically disconnect said contacts when either the main or auxiliary cover is open.

3. In combination, a casing, an insulating block 30 stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said cir-

cuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 5

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 10

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 15

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 20

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 25

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 30

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 35

4. In combination, a casing, an insulating block stationarily mounted within the casing, circuit connectors mounted on said block, at least one pair of switch contacts mounted on said block so as to be substantially protected from being accidentally touched, a switching member movable to electrically connect and disconnect said pair of switch contacts, means for electrically connecting one switch contact with one of said circuit connectors, said means including a fuse receiving device mounted on said block, an openable main cover for closing the front of the casing, said cover including an apertured portion so positioned with respect to said block that when the cover is closed access through the front of the casing may be had to said fuse receiving device for fuse replacement but not to the circuit connectors, releasable means for securing the main cover in closed position, and an openable auxiliary cover for closing the aperture in the main cover and for covering the main cover securing means, said auxiliary cover including means by which it may be secured in closed position against unauthorized opening. 40

JOSEPH A. CLINTON.
